MEANS FOR CONTROLLING LOOM HARNESSES
Price Walter Morrison, Chester, S.C., assignor to The
Springs Cotton Mills, a corporation of South Carolina
Filed Mar. 22, 1961, Ser. No. 97,544
10 Claims. (Cl. 139—80)

This invention relates to means for controlling the harnesses of a loom during weaving, and more particularly to means for controlling the harnesses by periodically restraining the harnesses in one position while more than one pick are being laid in the shed.

Heretofore controlling the shedding operation of loom harnesses has required special loom constructions, such as dobby looms and Jacquard looms, or other complex and expensive mechanisms. No simple and easily adaptable apparatus has been developed to control harnesses of simple looms, such as cam looms. Operation of these simple looms has been limited to plain weave patterns without variations in the shedding motion.

By the present invention, simple, practical and inexpensive means are provided for controlling loom harnesses so that the harnesses can be restrained in one position during the insertion of a number of picks in the shed to thereby produce a pattern in the cloth being woven, such as to produce a cord-like appearance.

The means of the present invention are applicable to various types of looms and in particular have been adapted to simple cam looms. It is easily attachable as a separate unit to existing looms without disassembling the loom and with a minimum of time and effort.

As compared with other devices, including loom constructions such as dobby looms, the present invention is simple and inexpensive to manufacture and attach to a loom, is easily and inexpensively maintained, and is easy to operate. More significantly, the present invention does not restrict or in any way reduce the speed of the loom operation, but will operate effectively at normal operating speeds of cam looms, which produce at a much greater number of picks per minute than do dobby looms that are limited in speed due to the complexity of the parts.

The control of the harnesses by the present invention is accomplished by actuating means operated by the drive motion of the loom, which actuate harness restraining means and take-up motion control means.

The actuating means includes a pattern device that operates in relation to the weaving operation of the loom to periodically operate the actuating means, which in turn operates the harness restraining means that engage and stop the harnesses in one position to allow a number of picks to be inserted in a single shed, and subsequently disengage the harnesses to permit the harnesses to resume their regular shedding motion.

The means for controlling the take-up motion are also controlled by the actuating means and are actuated simultaneously with the actuation of the harness restraining means so that when the harnesses are held in one position the take-up motion will be controlled to take up less warp. This is significant as less warp is needed per pick when the warp is dwelling in one shed position for a number of picks.

In the preferred embodiment of the present invention the actuating means comprises a pattern chain that is driven by the main drive shaft of the loom and is provided with indicator pins or other elements that periodically, in a selected pattern, engage and move an actuator arm. This actuator arm operates a slidable cable that extends to the harness restraining means to actuate said restraining means for holding the harnesses in one position.

The pattern chain of the actuating means is uniquely arranged in a horizontal position above the loom in a tray that carries a plurality of sprockets around which

2

the chain travels. In this arrangement the chain may be of substantial length and yet be compactly arranged to occupy a relatively small space, and more importantly to occupy the normally unused space above the loom without requiring additional floor space.

5 The pattern chain actuates a slidable cable that extends from the actuating means to the harness restraining means for actuation of the latter.

In the preferred embodiment the harness restraining 10 means comprises a treadle latch that is movable into the path of the harness treadle to engage the treadle and prevent movement thereof so that the treadle cannot move the harnesses from one position to another. This treadle latch is moved into the path of the treadle by a linkage 15 that is driven from the main cam shaft when actuated by the cable from the actuating means.

The means for controlling the take-up motion comprises a linkage for disengaging the gears of the conventional take-up mechanism and is operated from a linkage 20 of the harness restraining means so that the harnesses and the take-up motion are simultaneously controlled.

The actuation of the harness restraining means and take-up control means is timed to occur when the treadle is at the end of a normal stroke and the harnesses are 25 holding the warp in one of the open shed positions. When actuated the treadle latch moves into the path of the treadle and holds the treadle in this position when it would normally be moving to the opposite position. The treadle latch is then released while the treadle remains in 30 the same position as this is again the normal position. Thus, the harnesses will be in one position during the laying of three consecutive picks, i.e., the position immediately prior to latching, the latching position, and the position immediately following the latching position, which 35 is the position that the harnesses would normally be in at this point.

If desired the actuating means can be designed to actuate the harness restraining means to move the latch into treadle engaging position on two or more alternate 40 strokes of the treadle so that the harnesses will remain in the same position for the first three picks and for two additional picks for each additional latch engagement, i.e., one pick to each additional latch position and another pick for each subsequent normal position, which is the same as the latch position.

During the insertion of picks while the harnesses are held in one position it is normally desirable that the warp be taken up slightly to accommodate the filling being inserted. This is accomplished in the preferred embodiment by actuating the means for disengaging the take-up motion only on the actual held stroke of the harness treadle. Thus with one latch engagement, during which three picks are inserted, the take-up will be disengaged for only one pick and for more than one latch engagement the take-up will be disengaged for only the actual latch engagements and not the preceding and following normal positions when the harnesses are normally in the same position as when latched.

From the above it is apparent that the present invention 60 provides a simple and practical means for controlling the harnesses of a loom so that the harnesses will be positively and directly restrained in one position while laying a plurality of picks. The apparatus is compact, requiring no additional floor space, and can easily be 65 adapted as an attachment to an existing loom without disassembly or substantial modification of the loom, and without restricting or slowing the normal production rate of the loom.

Other and further features and advantages of the present invention will be apparent from the following description and drawings, in which:

FIG. 1 is a front elevation view of a cam loom having

attached thereto the preferred embodiment of the means for controlling harnesses of the present invention;

FIG. 2 is a vertical sectional view taken along line 2-2 of FIG. 1;

FIG. 3 is a vertical sectional view taken along line 3-3 of FIG. 2;

FIG. 4 is a top plan view of the pattern chain and associated elements of the embodiment of FIG. 1; and

FIGS. 5 through 8 are diagrammatic views showing the relative positions of the elements of the harness control means during operation thereof.

The preferred embodiment of the harness control means 10 of the present invention, illustrated in the drawings, is constructed as an attachment to a cam loom 12 and is attached to the loom, with only minor modifications of the loom to drivingly connect the harness control means to the drive motion of the loom. The cam loom 12 illustrated in the drawings is a model X cam loom made by Draper Corporation, Hopedale, Mass. It is of conventional construction and is illustrated herein only as an example of a loom to which the present invention can be attached. The details of the elements of the loom will not be described except as they relate to the present invention, as these details are well known in the art.

As seen in FIG. 1, the loom 12 includes a frame 14 which supports and carries the other elements of the loom. The loom is driven by the main cam shaft 16 which is mounted transversely in the frame 14 and carries the harness treadle cam 18 that rotates with the shaft to reciprocate the harness treadle 20 that is pivotally mounted on the frame 14 and extends transversely with respect to the main cam shaft 16. The harness treadle 20 is connected by a strap 22 to the front harness 24. The rear harness 26 is connected to the front harness 24 by the straps 28 that extend over the pulleys 30 so that reciprocation of the harness treadle 20 will reciprocate the harnesses 24 and 26 from one shed position to the other. The rear harness 26 is connected by a strap 32 to a coil spring 34 that urges the front harness 24 and harness treadle 20 into a raised position thereby maintaining the harness treadle 20 in following contact with the harness treadle cam 18.

Cloth is woven on the loom by the laying of filling picks between the warp yarns when the harnesses position the warp in open shed positions. The picks are laid by a shuttle (not shown) which is thrown across the loom by actuation of the picker sticks 36.

As the cloth is woven it is wound on the take-up roll 38 by means of a take-up mechanism 40 that is driven from the main cam shaft 16 through gears 42 and includes an axial clutch 44 that is operable to separate the gears 42 to disengage the take-up mechanism 40 and stop the take-up of the cloth on the roll 38.

The above described elements of the loom 12 are the conventional construction of the loom and it is in conjunction with these elements that the illustrated embodiment of the present invention is operated.

The harness control means 10 of the present invention includes actuating means 46 which actuate harness restraining means 48 that engage the harness treadle 20 and hold the harnesses 24 and 26 in one position. This embodiment also includes take-up motion control means 50 that are actuated by the actuating means 46 upon actuation of the harness restraining means 48 for disengagement of the take-up mechanism clutch 44 to stop take-up of the cloth on the take-up roll 38.

The actuating means 46 are efficiently and compactly mounted above the cam loom 12 on upright supports 52 that extend from the loom frame 14 and support a horizontally extending tray 54. This tray 54 contains a pattern chain 56 that extends back and forth a number of times within the tray 54 and extends around a number of idler sprockets 58 and one drive sprocket 60. In the embodiment illustrated there are eight idler sprockets

58 which in combination with the one drive sprocket 60 provide eight longitudinal and one transverse reaches for the chain. One of the idler sprockets, such as that indicated by the numeral 62, can be adjustably mounted for adjusting the tension of the chain 56.

The drive sprocket 60 is driven by a vertical drive rod 64 that is driven through bevel gears 66 by the main cam shaft 16. Thus the chain is continuously driven from the main drive motion of the cam and is timed in relation to other elements driven from the main cam shaft 16.

The pattern chain 56 carries vertically extending indicator pins 68 that are spaced along the chain in a selected pattern for actuation of the harness control means 10 of the present invention at desired times with respect to the operation of the loom.

A pivoted follower arm 70 is mounted in the tray 54 for pivotal movement in a horizontal plane. This follower arm 70 is located adjacent the drive sprocket 60 and has a follower finger 72 that extends into the path of the pins 68 on the chain 56 so that the pins 68 engage the finger 72. As the pins 68 move past the finger 72 they displace the finger and follower arm 70 causing the follower arm to pivot about the pivotal connection 74 at which it is mounted to the tray 54. This displacement causes the outer end 76 of the follower arm 70 to move away from a stop bracket 78 and displace a slidable pin 80 that is on the end of a slidable cable 86.

The slidable pin 80 is carried in a housing 82 and is maintained in contact with the outer end 76 of the follower arm 70 by a coil spring (not shown) in the housing 82 so that movement of the arm 70 displaces the pin 80 and the cable 86. The cable 86 is carried in a cable tube 84 that extends from the tray 54 of the actuating means 46 to the harness restraining means 48 for actuation thereof.

In the preferred embodiment the tray 54 contains an oil bath and is completely sealed to protect the chain 56 from foreign matter so that operation of the actuating means 46 can continue with little or no maintenance problems.

The harness restraining means 48 that are actuated by the slidable cable 86 of the actuating means 46 are mounted beneath the harnesses 24 and 26 and adjacent the harness treadle 20. The harness restraining means 48 of the embodiment illustrated comprises a shaft 88 oscillatably mounted in bearings 90 on the loom frame 14 and extending transversely with respect to the main cam shaft 16. The shaft 88 has fixed thereon an enlarged hub 92 which supports a housing 94 connected to the cable tube 84 and containing a slidable pin 96 at the end of the cable 86. The hub 92 has a lateral extension 98 on which is pivotally mounted an operating pawl 100. This pawl 100 has a flat side 102 in contact with the slidable pin 96 so that movement of the cable 86 will cause the pawl 100 to pivot.

An operating treadle 104 pivotally mounted on the loom frame 14 is driven by an operating treadle cam 106 on the main cam shaft 16 for reciprocation of the operating treadle 104. This operating treadle 104 is engageable with a lip 108 extending from the pawl 100 on the side opposite the pin contacting side 102. The pawl is weighted and balanced so that in its normal non-operating position the lip 108 is not in the path of the operating treadle 104, but upon actuation by movement of the cable 86 and resulting pivoting of the pawl 100 the lip 108 will be in the path of the operating treadle 104 for engagement and reciprocation thereby.

The pawl 100 is provided with a hub engaging extension 110 at the bottom thereof which in the non-operating position is spaced from a complementary surface 112 on the hub 92 and upon pivoting of the pawl 100 by the cable 86 the hub engaging extension 110 will abut the hub surface 112 so that reciprocation of the operating treadle 104 will be transmitted through the lip 108 and

hub extension 110 to cause the hub 92 and therefore the shaft 88 to oscillate.

The shaft 88 also carries a latch operating finger 114 that is fixed on the shaft for oscillation therewith. This finger 114 is connected by a strap 116 and hooks 118 to the top end of a latch member 120 that is mounted on a pivot pin 122 in a latch supporting framework 124. This framework 124 surrounds the harness treadle 20 and is slotted as at 126 to permit unhindered oscillation of the treadle 20. The latch member 120 is mounted alongside the harness treadle 20 and is pivoted by the latch operating finger 114 to position its lower end 128 above the harness treadle 20 when the harness treadle is in its lowermost position as seen in FIGS. 6, 7 and 8. The lower end 128 of the latch member 120 is inclined so that when it is pivoted into treadle engaging position it will be substantially parallel to the top of the treadle.

The elements of the harness restraining means 48 are maintained in the normal non-operating position of FIG. 3 by a spring 130 having one end 132 connected to the loom frame 14 and its other end 134 connected to a lever arm 136 extending from and fixed to the shaft 88.

The lever arm 136 also serves as the operating lever for the take-up motion control means 50 that is thereby actuated simultaneously through the common shaft 88 with the harness restraining means 48 upon operating of the actuating means 46.

A connecting rod 138 has one end 140 connected to the lever arm 136 and has its other end 142 connected to the base 150 of a V-shaped clutch operating member 144 that has one leg 146 pivotally connected to a fixed pivot pin 147 on the loom frame 14 and has its other leg 148 connected to the let-back lever 149 of the conventional take-up motion mechanism 40. The first leg 146 extends beyond the pivot pin 147 to form the yoke 152 of the standard clutch 44 of the conventional take-up mechanism 40.

The elements of the take-up motion control means 50 are arranged and adjusted so that when in the normal non-operating position the clutch 44 will position the gears 42 in driving relation and upon actuation of the take-up motion control means 50 the yoke 152 will be displaced and cause the clutch 44 to disengage the gears 42 by axial movement of the left hand gear 156 to the left out of engagement with the right hand gear 158.

The operating treadle cam 106 is shaped with relation to the harness treadle cam 18, as seen in FIG. 2, so that the operating treadle 104 will reach its lowermost position slightly after the harness treadle 20 has reached its lowermost position. These are the positions at which the treadles are at the extreme points of the cams. This relationship permits the harness treadle 20 to reach its lowermost position before the latch member 120 is pivoted by the operating treadle 104. This delay also results in the latch member 120 remaining in the path of the harness treadle 20 when the harness treadle begins its return stroke and is restrained in approximately its lowermost position by the latch member 120, which is prevented from pivoting further under the force of the harness treadle 20 by the opposite side of the latch supporting framework 124.

Although the operating treadle 104 moves through the return stroke, the latch member 120 remains in latching position as it is held in that position by the force of the harness treadle 20. During this period the harness treadle cam 18 is not in contact with the harness treadle 20. When the harness treadle cam 18 again reaches the normal down stroke position it again engages the harness treadle 20 and forces it to its lowermost position slightly out of engagement with the latch member 120, which falls out of its latching position to permit subsequent reciprocation of the harness treadle 20.

As a result of the above construction, the harnesses 24 and 26 remain in one position during three normal strokes for each actuation of the latch member 120. Thus the

harnesses are held in the down treadle position for the normal down treadle stroke, the latching stroke, which would be a normally up stroke, and the subsequent normally down stroke. During each of these strokes the shuttle is laying the filling pick in the shed and thus three picks are laid for each actuation of the latch member 120.

Each indicator pin 68 on the pattern chain 56 causes one actuation of the latch member 120 and therefore one pin by itself represents three picks being laid in a single shed. If it is desired to lay additional picks in the same shed, more than one pin can be arranged sequentially at points spaced equivalent to alternate strokes of the harness treadle 20 so that the latch member 120 will be actuated on consecutive down strokes of the harness treadle 20. Each additional pin, which results in an additional holding of the harness treadle, will cause two additional picks to be laid in the shed in addition to the three picks laid during actuation by the first pin. Thus each subsequent pin will cause the latch member 120 to hold the harness treadle in the down position for a normal up stroke, following which the harness treadle will be in the same position for its normal down position. In the embodiment illustrated the pairs 160 of pins will cause five picks to be inserted in one shed.

As the take-up motion control means 50 are operated from the shaft 88 of the harness restraining means 48 it is apparent that the clutch 44 disengages the gears 42 only during the single latching stroke of the harness treadle 20 and not during the preceding and subsequent strokes. Thus when three picks are being laid in one position of the harnesses the take-up motion is disengaged only during one of the three strokes. This permits partial take-up of the cloth, which is desirable to obtain a corded effect in the cloth. The period of disengagement of the take-up motion can be adjusted in any conventional manner as desired for best results for the particular cloth being woven and the particular yarn being used, or the take-up motion control means can be eliminated and the loom operated through the harness restraining operation with the take-up motion continuing uninterrupted.

The sequence of operation of the harness controlling means of the preferred embodiment to restrain the harnesses in the down-treadle position during two consecutive normal up-strokes is illustrated in FIGS. 5-8. These two held strokes, plus the preceding, intermediate, and subsequent normal down strokes, result in the harnesses remaining in one position for the insertion of five picks. This sequence is actuated by the pair of indicator pins 160, the first 162 of which is shown in displacing engagement with the follower arm 70 in FIG. 5. At this point the cable 86 actuates the pawl 100 to move it from its non-operating position of FIG. 3 into the path of the operating treadle 104. In the position of FIG. 5 the latch member 120 remains in the non-operating position, the harness treadle 20 has moved to its down position, the operating treadle 104 is about to engage the pawl 100, and the take-up motion control means 50 has not been actuated.

FIG. 6 shows the first pin 162 passing the follower arm 70, but the operating treadle 104 has already engaged the pawl 100, and has rotated the pawl 100 and shaft 88 to pivot the latch member 120 into the path of the harness treadle 20 and pivot the take-up control lever arm 136 to disengage the clutch 44 and stop the take-up mechanism 40. The harness treadle 20 is now in the down position with the harnesses in one position as a first pick is being laid.

FIG. 7 shows the subsequent up position of the operating treadle 104, which would normally also be the up position of the harness treadle 20, but the harness treadle 20 is now restrained in the down position by the latch member 120 to hold the harnesses in the first position while a second pick is being laid. In this position the first pin 162 has past the follower arm 70 and the second pin 164 is approaching the arm. The pawl 100, shaft 88

and lever 136 have returned to their normal position with the gears 42 again engaging to resume take-up.

The pressure of the harness treadle 20 holds the latch member 120 in this position until the next normal down stroke of the treadle, which is illustrated in FIG. 8, and during which a third pick is laid while the harnesses are still in the first position. As seen in FIG. 8, the elements are in the same position as FIG. 5, except that the second pin 164 is now engaging and displacing the follower arm 70 to actuate the harness restraining means 48 and take-up motion control means 50.

Following the position of FIG. 8 the elements move to the position of FIG. 6, but with the second pin 164 passing the arm 70. In this position the harnesses are again restrained in a down-treadle position during a normal up-stroke for the laying of a fourth pick in the first harness position.

On the subsequent down stroke the elements return to their original non-restraining positions with the latch member 120 falling back to its normal position when the treadle 20 moves to the down position to again position the harnesses in the same position as the fifth pick is being laid.

The loom then resumes normal plain weave operation with the elements remaining in their normal non-restraining positions of FIG. 3 until subsequently actuated.

In the above description one embodiment of the present application has been described in detail. However, it is to be understood that the present invention is not to be limited to the specific constructions described as it has application to many variations. The invention could be adapted to various types of looms other than a cam loom and the actuating means, harness restraining means, and take-up motion control means could be varied considerably in specific construction to accomplish substantially the basic purposes of the present invention. For example, the harness restraining means 48 need not be a mechanical linkage but could be an electrical device, as could the take-up motion control means. It is intended that the scope of the present invention not be limited except by the appended claims.

I claim:

1. Means for controlling the harnesses of a loom during weaving, said means comprising actuating means, harness restraining means engageable with the harness operating means of the loom to restrain the harnesses in one position while more than one pick are being laid in the same shed, said actuating means comprising pattern means, an actuator arm, and a longitudinally movable cable extending from said actuator arm to said harness restraining means and movable by said actuator arm to engage and actuate said harness restraining means, said actuating means periodically actuating said harness restraining means into said harness restraining engagement with the harness operating means.

2. Means for controlling the harnesses of a cam loom to hold the harnesses in one position while more than one pick are being laid in the same shed, said means comprising actuating means having pattern means driven from the main cam shaft of said cam loom for periodically operating said actuating means, harness restraining means engageable with the harness operating means of the loom to restrain said harnesses for retention of the harnesses in one position while more than one pick are being laid in the same shed said actuating means comprising a longitudinally movable cable and an actuator arm, said cable extending from the actuator arm to the harness restraining means and movable by said actuator arm to engage and actuate said harness restraining means into engagement with said harness operating means, said actuator arm periodically moving said cable to actuate said harness restraining means.

3. Means for controlling the harnesses of a cam loom to hold the harnesses in one position while more than

one pick are being laid in the same shed, said cam loom being of the type wherein the harnesses are operated by a harness treadle that reciprocates from one position to an opposite position, said means comprising actuating means having pattern means driven from the main cam shaft of said cam loom for periodically operating said actuating means, harness restraining means having an oscillatable shaft and a treadle latch connected to said shaft and movable into the path of said harness treadle upon oscillation of the shaft for engagement with the harness treadle to latch said treadle in one position and prevent reciprocation thereof while latched, said actuating means actuating said harness restraining means to move said treadle latch into latching position upon periodic operation of said actuating means by the pattern means, and take-up motion control means connected to said shaft and operable upon oscillation of said shaft to reduce the amount of take-up when said treadle latch is in latching position.

4. Means for controlling the harnesses of a loom during weaving, said means comprising actuating means, a horizontally extending chain support mounted above said loom, a plurality of rotatable sprockets mounted on said horizontal support in a substantially horizontal plane, at least one of said sprockets being driven by the drive motion of the loom, a pattern chain supported in a substantially horizontal plane on said support and sprockets and driven by said at least one sprocket, an actuator arm and a longitudinally movable cable connecting said actuator arm and the harness restraining means, said pattern chain periodically in a selected pattern operating said actuator arm and cable, harness restraining means actuated by said actuating means upon operation thereof by the pattern chain, said harness restraining means being engageable with the harness operating means of the loom to restrain said harnesses upon said actuation for retention of the harnesses in one position while more than one pick are being laid in the same shed.

5. Means for controlling the harnesses of a loom during weaving, said means comprising actuating means having a pattern chain arranged horizontally above said loom with a plurality of sprockets around which said chain travels and means for driving said chain from the drive motion of the loom, indicator pins carried by said chain and spaced thereon in a selected pattern for controlling the harnesses, a contact member mounted adjacent said chain for engagement with and displacement by said indicator pins as they move thereby, a cable tube mounted adjacent said contact member and extending therefrom, a slideable cable carried in said cable tube and having one end positioned adjacent said contact member for engagement thereby upon displacement of the contact member to slide the cable in the cable tube, harness restraining means engageable with the harness operating means of the loom to restrain said harnesses, said cable tube extending to said harness restraining means and said cable being engageable with said harness restraining means for actuation thereof upon displacement of the contact member by the indicator pins to cause the harness restraining means to engage the harness operating means and hold the harnesses in one position while more than one pick are being laid in the same shed.

6. Means for controlling the harnesses of a loom during weaving, said means comprising a latch member mounted on said loom and movable into engagement with the harness operating mechanism of the loom to restrain movement of the harnesses, a reciprocating operating member mounted on said loom and driven by the drive motion of the loom, a latch operating linkage connected to said latch member and engageable with said operating member for movement of said latch member into engagement with the harness operating mechanism, means for moving said latch operating linkage periodically into engagement with said operating member in a selected pattern for actuation of said linkage to move said latch member

into engagement with the harness operating mechanism to restrain the harnesses.

7. Means for controlling the harnesses of a loom during weaving, said means comprising a latch member mounted on said loom and movable into engagement with the harness operating mechanism of the loom to restrain movement of the harnesses, a reciprocating operating member mounted on said loom and driven by the drive motion of the loom, an oscillatable latch operating linkage connected to said latch member and operable upon oscillation to move said latch member into harness restraining engagement with the harness operating mechanism, said latch operating linkage having a pawl thereon moveable into the path of said reciprocating member for engagement thereby to oscillate said latch operating linkage and move the latch member into harness restraining position, means for moving said pawl periodically into the path of said operating member in a selected pattern.

8. Means for controlling the harnesses of a loom during weaving, said means comprising a latch member mounted on said loom and movable into engagement with the harness operating mechanism of the loom to restrain movement of the harnesses, a reciprocating operating member mounted on said loom and driven by the drive motion of the loom, an oscillatable latch operating linkage connected to said latch member and operable upon oscillation to move said latch member into harness restraining engagement with the harness operating mechanism, said latch operating linkage having a pawl thereon movable into the path of said reciprocating member for engagement thereby to oscillate said latch operating linkage and move the latch member into harness restraining position, means for moving said pawl periodically into the path of said operating member in a selected pattern, and take-up motion control means connected to said latch operating linkage for operation therewith, said take-up motion control means being engageable with the take-up motion of the loom to reduce the amount of take-up upon operation of the latch operating linkage.

9. Means for controlling the harnesses of a cam loom during weaving, said cam loom having a harness treadle reciprocated by a cam on a main cam shaft to reciprocate warp harnesses from one open shed position to the opposite open shed position, said means comprising a latch member pivotally mounted on said loom adjacent said harness treadle and movable into the path of the harness treadle to restrain movement of the treadle, a reciprocating operating treadle mounted on said loom, an operating treadle cam on said shaft engaging said operating treadle for reciprocation thereof, an oscillatable latch operating linkage connected to said latch member and operable upon oscillation to move said latch member into the path

of said harness treadle, said latch operating linkage having a pawl thereon movable into the path of said operating treadle for engagement thereby to oscillate said latch operating linkage and move the latch member into the path of the harness treadle, means for moving said pawl periodically into the path of said operating treadle in a selected pattern, the harness treadle cam and the operating treadle cam being related so that the latch member engages and restrains the harness treadle as it starts to move to the opposite position, the harness treadle thereby being in the same position when latched as in the previous and subsequent normal positions.

10. Means for controlling the harnesses of a cam loom during weaving, said cam loom having a harness treadle reciprocated by a cam on a main cam shaft to reciprocate warp harnesses from one open shed position to the opposite open shed position, said means comprising a latch member pivotally mounted on said loom adjacent said harness treadle and movable into the path of the harness treadle to restrain movement of the treadle, a reciprocating operating treadle mounted on said loom, an operating treadle cam on said shaft engaging said operating treadle for reciprocation thereof, an oscillatable latch operating linkage connected to said latch member and operable upon oscillation to move said latch member into the path of said harness treadle, said latch operating linkage having a pawl thereon movable into the path of said operating treadle for engagement thereby to oscillate said latch operating linkage and move the latch member into the path of the harness treadle, means for moving said pawl periodically into the path of said operating treadle in a selected pattern, the harness treadle cam and the operating treadle cam being related so that the latch member engages and restrains the harness treadle as it starts to move to the opposite position, the harness treadle thereby being in the same position when latched as in the previous and subsequent normal positions, and take-up motion control means connected to said latch operating linkage for operation therewith, said take-up motion control means being engageable with the take-up motion of the loom to reduce the amount of take-up upon operation of the latch operating linkage.
